(57) **CLAIM**

The ornamental design for a vehicle center console, as shown and described.

DESCRIPTION

FIG. 1 is a top-front-perspective view of a vehicle center console in a non-deployed position showing our new design. FIG. 2 is a right-plan view of the vehicle center console of FIG. 1.

FIG. 3 is a left-plan view of the vehicle center console of FIG. 1.

FIG. 4 is a front-plan view of the vehicle center console of FIG. 1.

FIG. 5 is a rear-plan view of the vehicle center console of FIG. 1.

FIG. 6 is a top view of the vehicle center console of FIG. 1.

FIG. 7 is a bottom view of the vehicle center console of FIG. 1.

FIG. 8 is a top-front-perspective view of the vehicle center console of FIG. 1 now shown in a deployed position.

FIG. 9 is a right-plan view of the vehicle center console of FIG. 8.

FIG. 10 is a left-plan view of the vehicle center console of FIG. 8.

FIG. 11 is a front-plan view of the vehicle center console of FIG. 8.

FIG. 12 is a rear-plan view of the vehicle center console of FIG. 8.

FIG. 13 is a top view of the vehicle center console of FIG. 8; and,

FIG. 14 is a bottom view of the vehicle center console of FIGS. 8.

In FIGS. 1 through 14, the broken lines are for illustrative purposes, boundaries, and structural support for the vehicle center console, and form no part of the claimed design.
